CLAIM

The ornamental design for an automatic feeding device for pets, as shown and described.

DESCRIPTION

FIG. 1 is a front elevational view of an automatic feeding device for pets showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a top, front and right side perspective view thereof; and,
FIG. 8 is a bottom, rear and left side perspective view thereof.

The broken lines in the drawings illustrate portions of the automatic feeding device for pets which form no part of the claimed design.

1 Claim, 8 Drawing Sheets
